UNITED STATES PATENT OFFICE.

JOHN D. MACDONALD, OF BOSTON, MASSACHUSETTS, ASSIGNOR TO FORBES LITHOGRAPH MANUFACTURING COMPANY, OF BOSTON, MASSACHUSETTS, A CORPORATION OF MASSACHUSETTS.

FOLDABLE STRUCTURE.

Application filed August 2, 1919. Serial No. 314,955.

To all whom it may concern:

Be it known that I, JOHN D. MACDONALD, a subject of the King of Great Britain, and a resident of Boston, county of Suffolk, and 5 State of Massachusetts, have invented an Improvement in Foldable Structures, of which the following description, in connection with the accompanying drawings, is a specification, like characters on the drawings 10 representing like parts.

This invention relates to foldable structures which are provided with means for holding them in their extended position. In particular, the invention is applicable to 15 structures made of sheets of card or the like, and as an example thereof I have here illustrated a box or carton having a lid which may be held in raised position serving, for example, to display a suitable advertisement 20 on the inside of the lid calling attention to the contents.

My invention may best be understood by reference to the following description of the illustrative embodiment thereof shown in 25 the accompanying drawings wherein:

Figure 1 is a front elevation of a cardboard box or carton embodying my invention, the box having the lid in raised position;

30 Fig. 2 is a section on the line 2—2 of Fig. 1;

Fig. 3 is a fragmentary elevation showing the lid raised but not held in position; and

Fig. 4 is a central transverse section 35 through the closed box.

Referring to the drawings, I have there shown a card-board box or carton having a back side 5 to which is hingedly connected the sheet 7 which forms the lid, the hinge 40 connection in this instance being a crease of the material. Across the line of junction between the back and the lid I may cut slits 9, there being herein two which are substantially centrally positioned. These slits define a strip 11 the ends of which are secured and, in the present instance because of the flexibility of the material, hingedly secured to the back 5 and the lid 7 respectively. As 45 shown in Fig. 4, when the box is closed the strip 11 will conform to the shape thereof and lie substantially in the planes of the back and lid.

To hold the lid in its raised position, as

shown in Fig. 1, I may provide a suitable brace cooperating with the strip 11 to hold the same displaced in such a manner that it forms a support for the lid. Herein this brace takes the form of a piece of card 13 wider than the strip 11, whereby it may be adjusted to the position shown in Fig. 2, 55 extending as a strut or brace bearing on the back 5 and lid 7 at the line of junction and on the strip 11 at the corresponding hinging line therein. The piece 13 may be provided with an extension 15 whereby it may 60 be hingedly secured in position, conveniently as shown, on the strip 11; and in the closed position of the box it will lie flat beneath the strip, as shown in Fig. 4, the 65 box being then in condition for use as a 70 shipping or storage package.

When the box is received and the lid is raised, the parts will come to the position shown in Fig. 3, the element 13 being still folded beneath the strip 11. It will usually 75 be found that a slight reverse bending of the lid beyond the perpendicular will cause the strip 11 to spring out somewhat toward the position in Fig. 2. In any event, the parts being in the position of Fig. 3, the piece 13 may be bent downwardly about its hinge, a finger tab 17 being conveniently provided to facilitate this; and it will then take the position shown in Fig. 2 where it 80 will hold the cover raised. As will be seen 85 from Fig. 2, the parts form a truss supporting the cover, the strip 11 constituting the chord of the truss, and the piece 13 a strut; but this truss is foldable to permit the parts 90 to be collapsed and when so folded will lie flat substantially in the planes of the elements which it supports in its open position.

I have herein described in detail the form of my invention illustrated as an example in the accompanying drawings, but it will be understood that the description has been thus specific in order that the construction of that particular form might be clear and not because the invention is correspondingly limited. The principles exemplified by the 95 particular disclosure herein made which I claim as new I shall express in the following claims:—

1. A foldable structure comprising hingedly associated sheet-like elements of card 100 or the like slotted across the line of junction

to provide a relatively movable strip connected at its ends to the sheets and having a hinged brace on one side of the strip.

2. A foldable structure comprising hingedly associated sheet-like elements of card or the like having a pair of slits across the line of junction providing a strip connected at its ends to the sheets and associated positionable means for holding displaced the body of the strip.

3. A foldable structure comprising hingedly associated sheet-like elements of card or the like having a pair of slits across the line of junction providing a strip connected at its ends to the elements and a wider tab hinged to the strip at the line of junction.

4. A foldable structure comprising hingedly associated sheet-like elements, a strip crossing the line of junction having its ends

secured to the elements and its middle portion free and a brace arranged for adjustment to prop said middle portion.

5. A box having a side and a hinged lid elements hingedly connected to side and lid respectively and to each other and adapted to lie substantially in the plane of back and lid when the box is closed with the joint between them at the line of junction and a wider flat element hinged to lie flat beneath one of said first elements.

6. A box having a side and a hinged lid and a truss for holding the lid raised comprising a chord and a strut relatively foldable to lie substantially flat in the planes of side and lid when the lid is down.

In testimony whereof, I have signed my name to this specification.

JOHN D. MACDONALD.
